HENRY SYNCK AND BRUCE B. ROLLMAN, OF COLDWATER, OHIO, ASSIGNEES TO NEW IDEA SPREADER CO., OF COLDWATER, OHIO.

FEEDING MECHANISM FOR MANURE-SPREADERS.

1,205,813.

Specification of Letters Patent. Patented Nov. 21, 1916.

Application filed May 16, 1916. Serial No. 97,882.

To all whom it may concern:

Be it known that we, HENRY SYNCK and BRUCE B. ROLLMAN, citizens of the United States, residing at Coldwater, in the county 5 of Mercer and State of Ohio, have invented certain new and useful Improvements in Feeding Mechanism for Manure-Spreaders, of which the following is a specification.

This invention relates to means for feeding the conveyer of a manure spreader so that the load will be carried to the pulverizer cylinder or beaters, the object of the invention being to provide a simple and efficient mechanism by which any desired 10 feed of the conveyer may be effected and back motion of the same positively prevented.

A further object of the invention is to provide novel means whereby the feeding 20 mechanism may be thrown out of action when desired without stopping the operation of the pulverizer or beater, and a still further object of the invention is to provide means whereby the remnants of a load 25 may be discharged even though the pulverizer may be at rest.

A still further object of the invention is to provide means whereby the parts may be readily adjusted to compensate for wear.

All the several stated objects and such other incidental objects as will appear from the following description are attained in the mechanism illustrated in the accompanying drawings and the invention resides in certain 30 novel features which will be particularly pointed out in the claims following the description.

In the accompanying drawings: Figure 1 is a side elevation of so much of a manure 40 spreader body or wagon as is necessary for a disclosure of our improvements; Fig. 2 is a perspective view of the front end of the wagon body; Fig. 3 is a plan view of the mechanism shown in Fig. 1; Fig. 4 is a 45 elevation of a modification; Fig. 5 is a similar view showing a further modification; Fig. 6 is a detail perspective view of one of the feeding dogs.

In the drawings, the reference numeral 1 50 indicates a portion of a wagon body which is employed to contain the load in manure spreaders and the bottom of which consists of an endless apron or similar form of conveyer actuated by sprocket chains, a portion 55 of one of which is seen at 2 in Fig. 1, which

are secured to the side edges of the apron and engage sprocket wheels on a shaft 3 which is mounted in suitable bearings at the rear end of the wagon body. Upon this shaft 3 at one side of the body is secured a 60 ratchet wheel 4 which is actuated by mechanism mounted upon the side of the body and operated from the rear axle 5 to impart an intermittent motion to the apron or conveyer. The axle 5 is mounted in suitable bearings upon the wagon body and extends transversely below the same and between the upper and lower runs of the conveyer, the ground wheels being mounted upon the axle and adapted to actuate the 70 same through an ordinary escapement which is indicated at 6 in dotted lines. By means of this escapement, the ground wheels will rotate the axle as the machine is drawn forward over the field but will slip around the 75 axle without actuating the same if the machine be backed. The escapement also permits one wheel to travel faster than the other in turning corners so that the movement of the axle will be uniform.

In carrying out our present invention, we secure upon the axle 5 a plurality of cams 7 which consist of castings having hub members equipped to be keyed or otherwise fixed upon the axle 5 and diametrically opposite 80 cam arms projecting radially from the hub members. While any desired number of these cams may be provided, we have found two cams placed as shown in the accompanying drawings with their working arms 90 disposed at right angles to each other to be sufficient for all ordinary purposes. Upon the side of the wagon body, above the axle, we secure a bracket or casting 8 having a lateral pin 9 projecting therefrom and upon 95 this pin we pivotally hang oscillatory arms or levers 10 which depend from the said pin in the planes of the respective cams 7. The lower ends of these lever arms are recessed to receive rollers 11 which ride upon the 100 surfaces of the radially projecting arms of the cams 7 so that, as the cams rotate, the said lever arms will be oscillated without excessive friction or unnecessary wear. Upon the sides of each of said levers, at 105 the lower ends thereof, we provide perforated lugs 12 to which we pivotally attach the front ends of the bars 13 which form parts of the actuating dogs. The dogs 14 may be formed integral with the rear 110

ends of the bars 13 so that the said bars will form the shanks of the dogs, but we prefer to construct these members as illustrated most clearly in Fig. 6, in which the dogs 14 are shown as consisting of plates provided with longitudinal slots 15 to receive securing bolts 16 carried by the shanks or bars 13 whereby the dogs may be adjusted longitudinally of the shanks, thereby compensating for wear upon the parts. The forward end of the dog is upturned, as shown at 17, and an angular bracket 18 is rigidly secured upon the shank 13 adjacent but in spaced relation to the said upturned end 17. A bolt 19 is inserted through and carried by the bracket 18 and the upturned end 17 and liners or washers 20 are fitted around the bolt between the said members 17 and 18 so that, by removing the washers or liners, or inserting additional washers or liners, the point of the dog 14 may be set at any desired distance from the pivotal point of the bar 13. This adjustability of the device is desirable to accommodate unevennesses or inequalities produced in the process of casting some of the members so that, without involving heavy expense in the manufacture of the mechanism, a very accurate and smoothly operating apparatus may be produced.

The free ends of the dogs play through and are supported and guided by brackets 21 secured on the side of the wagon body 1, as clearly shown in Figs. 1 and 3, and these guides may be of any preferred construction. To prevent retrograde movement of the ratchet wheel 4 and the conveyer, we provide holding dogs or pawls 22 which are pivotally mounted upon a bracket 23 secured on the side of the wagon body, adjacent the ratchet wheel, so as to engage the teeth thereof. These holding dogs or pawls may be provided in any desired number, but ordinarily two will be sufficient, it being understood that the pawls will be of unequal length. The difference in length of the dogs 22 will preferably be equal to one-half the distance between the points of adjacent ratchet teeth so that it will be possible to stop backward movement of the conveyer at the end of each period of movement equal to one-half the spacing of the teeth. Approximately, by this arrangement, there is always one dog in engagement with a tooth of the ratchet wheel so that retrograde movement of the conveyer cannot occur in any degree. This result may be accentuated by using a greater number of holding dogs and having the difference in the length of the same more minute.

It will be readily noted that the guide 21 prevents lateral movement of the feeding pawls 13 and this guide may be also utilized as a guide and support for the rear extremity of the adjusting member 24. The said member 24 consists of a bar having its front portion slidably mounted in a guide 25 provided upon the side of the wagon body and having a collar or sleeve 26 pivoted to its front end. A connecting rod 27 is secured in the said sleeve or collar 26 and extends to the front end of the wagon body where it passes through a sleeve or ring 28 pivoted to the lower end of a hand lever 29 and has its front extremity pivotally connected with an arm 30 depending from a rock shaft 31 mounted upon a cross bar 32 at the front end of the body and constituting the fulcrum of a foot lever or treadle 33. Stop collars 34 are secured upon the rod 27 in front and in rear of the ring or sleeve 28 and a spring 35 is coiled around the rod between the front stop collar 34 and the front end of the sleeve 28. The lever 29 is fulcrumed upon the side of the wagon body between its ends and is equipped at its upper end with a latch 36 adapted to engage a holding segment 37 fixed upon the body adjacent the lever and concentric with the fulcrum of the same. The member 24 passes between the levers 10 and is provided upon its sides with retaining loops or guides 38 which pass around the said levers, as will be readily understood upon reference to Figs. 1 and 3. The forward ends of the retaining loops or guides 38 are closed so that if the member 24 be shifted rearwardly, the said forward ends of the loops will be brought close to the respective levers 10 and thereby limit the forward movement of the same. It will thus be readily understood that the throw of the levers and of the feeding pawls carried thereby, may be very easily and readily regulated and if the bar be moved rearwardly to its full extent, the levers will be held beyond the paths of the cams 7 so that they will not be operated and the conveyer will not feed. To obtain accuracy in the adjustment, as well as to compensate for wear or roughness or inequality in the castings, we mount set screws 39 in the forward ends of the retaining loops 38 which are adapted to project into the path of movement of the levers 10 and thereby arrest the forward swing of the same, as will be readily understood.

It is thought the operation of our improved mechanism will be readily understood from what has gone before. When spreading of the fertilizer is about to begin, the lever 29 is adjusted so that the levers 10 will be set to permit such adjustment of the feeding pawls as will impart to the conveyer the required speed to accomplish the proper feeding of the load. As the machine is then drawn over the field, the cams 7 will engage the lower ends of the levers 10 and oscillate the same and the feeding pawls whereby intermittent movement of the ratchet wheel 4 will be effected. When the

- adjusting member 24 is moved rearwardly, the forward movement of the levers 10 will obviously be limited by the front edges of said levers coming into contact with the 5 front ends of the retaining loops or guides 38 and, consequently, the lower ends of the levers will not engage the cams as close to the hubs thereof as when the member 24 is in its extreme forward position. It will be 10 readily noted that the spring 35 tends to hold the sleeve 28 against the rear stop collar 34 and, consequently, if the lever 29 be swung forward to the front end of the segment 37, the feeding mechanism will be held 15 inoperative so that the machine may be moved from one field to another field or may be driven back to the barn to be reloaded without causing any movement of the conveyer and unnecessary wear upon the 20 working parts is thus avoided.
- When the machine is in operation and distributing fertilizer, the lever 29 is permitted to remain at rest in the position to which it has been adjusted and should it then be desired 25 to temporarily stop the feeding, as at the end of the field when turning or when reaching a place where fertilizer is not needed or desired, the foot lever 33 is pressed downwardly, thereby swinging the arm 30 rearwardly and, consequently, pushing the connecting rod 27 rearwardly, the said rod sliding through the sleeve 28, as will be readily understood. The movement of the rod 27 will be transmitted directly to the bar 24 30 and, consequently, the retaining loops 38 will be caused to hold the levers 10 out of engagement with the cams 7 so that the feeding will not take place. When it is desired to again feed, the treadle 33 is released and the 35 spring 35 will at once expand and return the parts to their former positions. It will be understood, of course, that the pulverizing and distributing elements are controlled independently of the feeding mechanism and, 40 consequently, the pulverizing and distributing members may be stopped when the load is about exhausted while the conveyer may continue to operate so that the remnants of the load which may be left upon the conveyer will be carried out of the machine. It 45 is also possible to stop the machine and while it is at rest discharge the few remnants of the load by merely working the treadle 33 up and down a few times. It will 50 also be noted that the rapidity of the feeding may be changed and accurately regulated without stopping the travel of the machine over the field, inasmuch as this is accomplished by setting the lever 29 which is 55 disposed at the front end of the machine where it may be conveniently reached by the right hand of the driver. It will be noted that at each revolution of the axle or driving shaft to which the cams are secured, the 60 ratchet wheel will be moved four times, in 65 the arrangement illustrated, so that the load will be fed rapidly to the beaters and the intervals of rest will be just long enough to permit the beater teeth to properly take into and disintegrate the portion of the load immediately adjacent the same. 70
- It may sometimes be desirable not to have the points of the feeding pawls carried directly by the oscillating levers, as in the arrangement illustrated in Fig. 1 and heretofore described. In Fig. 4, we illustrate an arrangement in which the dogs or feeding pawls 40 are pivoted upon the levers 41 near the upper ends thereof, said levers being mounted upon the shaft 42 of the conveyer 75 and links 43 being interposed between the upper ends of the levers 41 and the oscillatory levers 44, which correspond to the levers 10, and are actuated by cams 45. In this arrangement, the pawls will operate directly 80 over the ratchet wheel and no part of the weight of the same is carried by the guide 85 46 or by the ratchet wheel, the levers 41 serving to transfer the weight to the shaft 42.
- In Fig. 5 we illustrate a further modification in which the two feeding pawls 47 and 48 are arranged in the same vertical plane and actuated by a single cam member 49, the upper pawl 47 being connected with a lever 50 which is disposed in approximately 90 the same position as the levers 10 shown in Fig. 1, while the lower pawl is pivoted to the rear end of a lever 51 fulcrumed between its ends on the side of the wagon body and having its forward end arranged to be actuated 95 by the cam member 49 alternately with the lever 50. The adjusting rod 52 has its rear end pivoted to a three-armed lever 53 fulcrumed upon the side of the wagon body in rear of the lever 50 and the downwardly and 100 rearwardly extending arms of this lever 53 carry sleeves 54 and 55 respectively, through which pass rods 56 and 57 extending respectively to the levers 51 and 50 to which they are attached. Stops 58 are provided upon 110 these rods and adapted to be engaged by the sleeves 54 and 55, as will be readily understood. In this arrangement, the adjusting rod 52 will be drawn forward to arrest or regulate the feeding, the forward movement 115 of the rod serving to swing the lever 53 about its fulcrum so that the sleeves 54 and 55 will engage against the collars 58 and thereby draw upon the levers 50 and 51 so as to hold the operating ends of the same at the 120 desired distance from the hub of the cam member.
- Having thus described the invention, what is claimed as new is:
1. In a mechanism for the purpose set forth, 125 the combination of a ratchet wheel, a feeding pawl engaging said ratchet wheel, an oscillatory lever connected at its free end with said pawl, means for actuating said lever, an adjusting member, a retaining loop 130

on the side of said member fitting around the lever, and an adjustable stop in one end of said loop to engage the lever.

2. In mechanism for the purpose set forth, 5 the combination of a ratchet wheel, a plurality of feeding pawls engaging said ratchet wheel, a plurality of oscillatory levers each connected at its free end with one of the feeding pawls, a single adjusting rod, means 10 actuated by said rod for holding all the levers inoperative, and means for adjusting said last-mentioned means whereby to regulate the extent of oscillation of the several levers.

15 3. In mechanism for the purpose set forth, the combination of a ratchet wheel, a pair of feeding pawls engaging the ratchet wheel, a pair of oscillatory levers connected at their 20 free ends with the feeding pawls, cams acting upon the free ends of the respective levers, an adjusting member passing between the levers, and retaining loops mounted on the sides of said adjusting member and fitting around the levers and adapted to engage 25 gage the same to limit the movement thereof.

4. In mechanism for the purpose set forth, the combination of a ratchet wheel, a pair of feeding pawls engaging the ratchet wheel, a pair of oscillatory levers connected at their 30 free ends with the feeding pawls, cams acting upon the free ends of the respective levers, an adjusting member passing between the levers, retaining loops mounted on the sides of said adjusting member and fitting 35 around the levers and adapted to engage the same to limit the movement thereof, and stops adjustable through the ends of the retaining loops to impinge against the levers.

5. In mechanism for the purpose set forth, 40 the combination of a ratchet wheel, a feeding pawl engaging the ratchet wheel, means for oscillating said pawl, adjustable means for regulating the throw of the pawl, and means for holding the pawl inoperative independently of the adjustment of the means 45 for regulating the throw of the pawl.

6. In mechanism for the purpose set forth, 45 the combination of a ratchet wheel, a feeding pawl engaging the ratchet wheel, an adjusting bar arranged to limit the operative movement of the pawl, means for setting 50 said bar to permit a given movement of the

pawl, and other means for causing said bar to move the pawl to an inoperative position independently of the means for setting 55 the bar.

7. In mechanism for the purpose set forth, the combination of a ratchet wheel, a feeding pawl engaging said wheel, an adjusting bar arranged to regulate the throw of the 60 pawl, means for setting the bar in a given position, means for yieldably holding said bar in a set position, and means for actuating said bar to move the pawl to an inoperative position independently of the means for 65 setting the bar in a given position.

8. In mechanism for the purpose set forth, the combination of a ratchet wheel, a feeding pawl engaging the ratchet wheel, an adjusting bar arranged to regulate the throw of 70 the pawl, a hand lever having a slideable connection with the said adjusting bar, means for holding the lever in a set position, stop collars on said adjusting bar at opposite 75 sides of the sliding connection between the bar and the said lever, yieldable means acting on one of said collars for holding the adjusting bar in a set position, and a rock shaft connected with said bar to act on the same against the force of said yieldable 80 means independently of the said lever to move the feeding bar to an inoperative position.

9. In mechanism for the purpose set forth, 85 the combination of a ratchet wheel, a feeding pawl comprising a shank, a fixed bracket on the shank, a tooth slidably mounted on the shank and engaging the ratchet wheel, and an adjustable connection between said tooth and the fixed bracket. 90

10. In mechanism for the purpose set forth, the combination of a ratchet wheel, a feeding pawl engaging said wheel and comprising a shank, a fixed bracket on said shank, a tooth mounted on the end of the shank and adjustable longitudinally of the same, a connection between the fixed bracket and the end of the tooth, and spacers around 95 said connection between the end of the tooth and said bracket. 100

In testimony whereof we affix our signatures.
